Attorney

UNITED STATES PATENT OFFICE.

WALLER C. PARRISH, OF KANSAS CITY, MISSOURI.

PROPELLED MEANS.

1,311,415.

Specification of Letters Patent. Patented July 29, 1919.

Application filed January 11, 1919. Serial No. 270,655.

To all whom it may concern:

Be it known that I, WALLER C. PARRISH, a citizen of the United States, residing at Kansas City, in the county of Jackson and State of Missouri, have invented certain new and useful Improvements in Propelling Means, of which the following is a specification, reference being had to the accompanying drawings.

10 This invention relates to certain improvements in propelling means, and has relation more particularly to a means of this general character especially designed and adapted for use in connection with toys, and it is an 15 object of the invention to provide a novel and improved device of this general character including two rotatable members, such as axles, and with which an elastic band or strip coacts, together with means whereby 20 the band as it unwinds from one of the rotatable members is caused to wind around the second rotatable member.

The invention consists in the details of construction and in the combination and arrangement of the several parts of my improved propelling means whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawings, wherein:

Figure 1 is a view in side elevation illustrating a device constructed in accordance with the present embodiment of my invention; and

Fig. 2 is a view in top plan of the device as disclosed in Fig. 1.

As disclosed in the accompanying drawings, C denotes a body with which is operatively engaged the rotatable shafts A and B, the shaft A being arranged at the front of the portion of the body C and the shaft B at the rear portion of said body. As herein disclosed, the extremities of the shafts A and B, have affixed thereto the wheels W, although I do not wish to be understood as limiting myself in this respect, as other members may be fixed to the shafts A and B in lieu of the wheels W.

The rear shaft B has fixed thereto a drum

D to which is suitably secured an end portion of an elastic band or strip E, and which band is adapted to be wound around the drum to place said band or strip E under tension as the opposite end portion of the band or strip E is suitably secured to the front axle A. The band or strip E is also adapted to wind around the front axle A but reverse to the windings around the drum D. 60

M denotes a non-elastic flexible member or band secured at one end portion to the front axle A, and at its opposite end to the rear axle B, and said member or band M upon travel of the device causes the axles A 70 and B to rotate in unison as the windings of the strip or band E around the shaft B are reverse to the windings of the band or strip E around the drum D, and the windings of the member or band M around the front axle A is also reverse to the windings of the band or strip E around said front axle.

Initially, the rear shaft B is rotated to wind the band or strip E around the drum 80 D whereby said strip or band is placed under tension. At the same time, the unwinding of the member or strip E from the front shaft A causes the member or band M to wind around said front shaft. The tension 85 of the band or strip E causes the drum D to rotate, resulting in the requisite rotation of the shaft B and which rotation of the shaft B results in the member or band M being wound therearound to rotate the front 90 shaft A. The rotation of the shaft A results in the winding therearound of the band or strip E so that the tension or pulling power of said band or strip E is maintained as the winding thereof around the 95 front axle A prevents the band or strip E from becoming slack.

To rewind the device it is only necessary to pull the member or band M forwardly, as this operation will cause the elastic band or strip E to wind back on the drum D.

In the present embodiment of my invention, the wheels W carried by the rear axle B are each of a diameter substantially four times the diameter of the drum D, and as 105 the elastic band or strip E will stretch substantially five times its normal length, it will be at once self evident that the body B will be caused to travel a distance substantially equal to twenty times the length of the 110 band or strip E, and which is further assured in view of the fact that the energy

of the band or strip E is released uniformly due to the coaction of the member or band M with the axles A and B.

From the foregoing description, it is thought to be obvious that a propelling means constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

What I claim is:

20 1. A propelling means of the class described comprising two spaced members supported for rotation, an elastic band connecting said members and winding therearound, and a non-elastic flexible member connect-

ing the rotating members and adapted to wind therearound but in directions reverse to the windings of the elastic band on the same member.

2. A propelling means of the class described comprising two members supported for rotary movement, an elastic band connecting said members and adapted to be wound therearound, said band when under tension rotating one of said members, and means coacting with the members for causing the same to rotate in unison upon rotation of one of the members by the tension of the elastic band, whereby the elastic band is caused to wind around the second member for maintaining the tension of the elastic band.

In testimony whereof I hereunto affix my signature in the presence of two witnesses.

WALLER C. PARRISH.

Witnesses:

G. W. MOORE,
C. C. BATES.
